TYPOGRAPHICAL COMPOSING MACHINE

Richard E. Sylte, Chicago, Ill., assignor to Intertype Corporation, Brooklyn, N. Y., a corporation of New York

Application October 24, 1939, Serial No. 300,905

10 Claims. (Cl. 199—19)

The present invention relates to improvements in typographical machines and more especially to those of the general class shown and described in U. S. Letters Patent No. 436,532, granted September 16, 1890, wherein fonts of character-bearing matrices stored in channeled magazines are released therefrom in response to manipulation of a keyboard and led to a common assembling point where they are composed into lines, the lines being presented before a slug casting mold and the matrices subsequently being delivered to distributing mechanism which returns the matrices to their proper places of storage in the magazines from which they were drawn.

The invention relates more particularly to machines of this class equipped with at least two main magazines preferably arranged in superposed relation, each magazine containing a complete font of matrices and each having associated therewith a series of matrix releasing escapements, and wherein the matrices from both fonts may be composed in the same line. Such machines are commonly known as "mixers" and are employed for composition requiring changes from one font or type face to another during the composition of a line, there being provided on the machine dual facilities or the equivalent thereof for assembling and distributing the matrices. In such machines the keyboard is common to both magazines and means is provided for rendering it operative selectively upon the matrix escapements for one or the other of the magazines. While different schemes may be employed for this purpose a convenient and widely used arrangement consists in providing keyboard operated escapement actuating devices which are shiftable or adjustable as a whole into cooperative relation either directly or indirectly with all of the matrix escapements of either one of the magazines each time a change from one font or type face to the other is required.

The primary object of the present invention is to enable the operator of a "mixer" machine to compose simultaneously from different selected ones of a plurality of portions of complete matrix fonts in two main magazines without the necessity of shifting the keyboard connections each time the composition requires a change from one magazine to the other. To elucidate, the characters comprising a complete font of matrices as ordinarily contained in a main magazine may be considered as divided into at least three different character groups or sets of matrices arranged within the magazine in contiguous groups of channels. With two superposed magazines,

which is the preferable arrangement, and with the font in each of them similarly divided into such a plurality of character groups, corresponding sets of characters will be superposed but the actual style or size of the characters in superposed groups may differ according to the particular fonts in use. Thus, in the upper magazine of a pair thereof the first group in a particular font may comprise a small cap alphabet, the second group the numerals and points (punctuation marks, etc.) of the font and the third group the regular capital letter alphabet of the font. In another font in the lower magazine the correspondingly disposed character groups may comprise a lower case alphabet, numerals and points, and a regular cap alphabet. In practice, however, many other combinations of character groups may be employed to meet the requirements of different classes of mixed composition and the number of groups may be increased. For example the numerals alone may comprise a fourth group and thus be susceptible to selective use with different character groups in the two fonts employed. With the particular character group arrangement recited above matter may be composed such as a list of names requiring the regular caps (third group) of the font in the upper magazine for the first letter in each name and small caps (first group) of the font in the lower magazine for the following letters in each name.

According to the present invention the time and attention of the operator need not be encroached upon in constantly shifting the entire set of keyboard connections in order to draw matrices from the different character groups in the two magazines, it being necessary only to decide at the outset the character groups in each of the fonts that are required for a given piece of composition and adjust the keyboard connections to suit. Thereafter, the composition may proceed uninterrupted, except in instances where a temporary adjustment may be necessary to secure certain characters from another group to complete the particular matter being composed.

To the end that adjustment of the keyboard operated escapement actuating connections or reeds relative to the escapements of different character groups in two main magazines may be reduced to a minimum, these connections, according to the present invention, are divided into as many groups as there are character groups in a single font, so that with superposed magazines each such group of connections will correspond to a pair of superposed character groups, that is,

each group of connections will be common to a corresponding group of finger keys on the keyboard and to the escapements of each of a pair of superposed character groups controlled by such finger keys. To enable connection of the keyboard simultaneously to different selected character groups in both magazines each group of keyboard connections is independently shiftable or adjustable, whereby any character group in one magazine may be selected for use simultaneously with one or more different or non-corresponding character groups in the other magazine, or all of the groups in either one of these two magazines may of course be selected for joint use.

Other arrangements have already been proposed for adjusting the keyboard connections in relation to different magazines on a machine, one such arrangement providing for connection of the keyboard as a whole to one magazine or in part to each of two magazines. This proposal, however, refers only to typographical machines with at least one main magazine and one auxiliary magazine (a narrow magazine containing only a single group of characters) arranged at one side thereof or in "tandem" thereto. The keyboard connections for this purpose not only fail to afford the facility of selection of different combinations of several character groups in two complete fonts but obviously also are not adapted to operate in connection with superposed character groups. In another arrangement it has been proposed, using at least three magazines, to connect the escapement actuating devices all to one magazine or simultaneously in part to each of two other magazines on a machine, the latter two magazines containing each a portion only of a font of matrices of an extra thick variety such as a capital alphabet of extra wide letters which are so large that each character is split vertically, one-half being provided on a matrix in one magazine and the other half on a matrix running in the adjacent channel of the other magazine. For this purpose alternate reeds are simply connected to alternate escapements of the two different magazines but all of the reeds cannot be connected only to one of these magazines. Here again, no facility is afforded for connecting the keyboard simultaneously to different selected portions of complete matrix fonts in two magazines superposed or otherwise.

In the accompanying drawings, one embodiment of the invention is shown, by way of example, as applied to one form or construction of a mixer machine and to superposed main magazines, and obviously many changes and variations may be made in the arrangement and combination of parts and the specific mode of operation thereof in adapting the invention to machines of somewhat different construction. It is to be understood, therefore, that the invention is not limited to any specific form or embodiment except insofar as such limitations are specified in the claims.

In the drawings:

Fig. 1 is a side elevation of a portion of a mixer machine to which the invention is applied.

Fig. 2 is a front elevation showing the keyboard connections of the invention arranged in independently adjustable groups.

Fig. 3 is a diagrammatic view showing the relation between the adjustable groups of keyboard connections and the superposed character groups in two superposed magazines.

Referring to the drawings, the numeral 1 designates the usual keyboard of a typographical machine of the class referred to, it having in the present instance ninety finger keys 2 and being supported by fixed frame members of the machine including the cast bracket 3 secured to the column (not shown) of the machine. A fixed frame 4 supports the assembler front 5 which comprises in this case two entrance throats 6 and 7 respectively for receiving matrices released from the upper magazine 8 and the lower magazine 9 in response to manipulation of the keyboard. The magazines 8 and 9 are main magazines of the usual trapezoidal shape each containing in well known manner a font of matrices arranged according to character in channels in the opposed plates thereof.

Keys 2 actuate, by mediation of well known mechanism contained in the rear of the keyboard housing, the vertically slidable escapement 10 actuating connections or reeds 11 of which there are ninety arranged in a row, one for each finger key. In a well known form of "mixer" machine these reeds ordinarily are supported in a single swinging frame so that they may be shifted as a unit into cooperative relation with one or another set of rods 12 or 13 arranged above them (ninety rods in each set) and extending respectively to the matrix escapements 12a and 13a of the upper and lower magazines 8 and 9. The rods 12 and 13 are guided for free vertical movement in slotted strips 14, 15, 16 secured to frame 4 and rock the escapements when actuated by the reeds 10 to thereby effect the release of matrices. The arrangement and operation of similar parts of a "mixer" machine are more fully disclosed in U. S. Letters Patent No. 1,542,774 granted June 16, 1925, to which reference may be had if desired.

As previously stated, the superposed magazines 8 and 9 are main magazines of the usual form containing each a font of matrices. Ordinarily, each magazine contains a different font, that is, different as to the design or the size of the type face carried on the matrices and the matrices are arranged in character groups which may differ according to requirements. Also, it may be stated here that the actual number of characters in different complete fonts may differ and it is to be understood that although the invention is discussed in connection with two ninety character fonts it may be applied equally well to seventy-two character fonts as commonly employed on these machines.

For purposes of illustration, in the present instance, the upper magazine 8 contains a complete ninety character font divided in groups comprising a small capital letter alphabet (26 characters) for the left hand group, numerals and points (punctuation marks) for the center group (38 characters) and a capital letter alphabet (26 characters) for the right hand group. These groups are superposed respectively over corresponding groups in the ninety character font in the lower magazine, such groups comprising, at the left, a lower case letter alphabet, in the center a numeral and point group, and at the right a capital letter alphabet. So far as the invention is concerned broadly it does not matter whether the actual characters in superposed character groups are alike or different character for character since it is well known that each finger key on the keyboard may carry more than one character designation and thus serve for different sets of characters.

As previously stated the object of the present invention is to enable the operator to compose not only selectively from different whole fonts as heretofore, but also simultaneously from different selected ones of a plurality of character groups or portions of fonts carried in two main magazines without performing a shifting operation for every change in the composition from one magazine to the other. For this purpose, according to the invention, the ninety reeds 10 are divided into three independently adjustable groups X, Y, and Z corresponding to the superposed sets of character groups in the magazines 8 and 9 and these groups of reeds are carried in separate shiftable frames 17, 18 and 19 respectively. Each group of reeds is operated by a corresponding group of finger keys with which they are constantly in operative relation. Since the arrangement of the characters and the grouping thereof on the finger keys of the keyboard is so well known it is deemed sufficient here merely to state that there are six horizontal rows of fifteen keys each, an alphabet group, usually the lower case alphabet being grouped on the set of keys at the left, the figures and marks on the center group of keys, and an alphabet group, usually the capital letter alphabet on the right hand group of keys.

Each of the frames 17, 18 and 19 is provided along the top edge thereof with a slotted strip 20 in which the reeds 10 are guided for vertical movement and at the lower end at each side the frames are provided with legs 21 tapered to bearing edges 22 on which they are adapted to rock in shallow grooves 23 on the keyboard frame. Frames 17 and 19 each carry a group of twenty-six reeds 10 adapted to actuate a corresponding number of upper rods 12 or 13 belonging to the right and left hand character groups in magazines 8 and 9. Frame 18 carries a group of thirty-eight reeds adapted to actuate a corresponding number of upper rods 12 or 13 belonging to the center character groups in the respective magazines. Thus, there are ninety reeds 10 as before but they are now divided into three independently adjustable groups so that the upper ends of the reeds in any group may be shifted into register with corresponding rods 12 or 13 merely by swinging the required frame 17, 18 or 19.

For independently adjusting the three frames 17, 18 and 19 and their respective groups of reeds there are provided three shift levers 24, 25 and 26 having knobs 24^a, 25^a and 26^a respectively and preferably arranged beside one another toward the right and above the keyboard within convenient reach of the operator. Lever 24 is loosely pivoted at 27 to the lower end of a lever 28, the latter being pivotally supported at 29 in a bracket 30 and having a fork 31 in the upper end thereof freely engaging a pin 32 fixed in lugs 33 projecting from the rear of frame 17. By pulling knob 24^a forwardly, from the full line to the dotted line position shown in Fig. 1, frame 17 and the twenty-six reeds 10 of group Z therein will be shifted from the full line to the dotted line position indicated, that is from operative relation with the upper rods 12 which control the escapements of the right hand character group (capital letter alphabet) in the upper magazine 8 into operative relation with corresponding upper rods 13 which control the escapements of the similarly disposed character group in the lower magazine 9. Obviously, by pushing knob 24^a rearwardly, frame 17 will be shifted forwardly

to thus restore the operative connection of the keyboard to the escapements of the character group in the upper magazine 8.

Reed frames 18 and 19 and the respective groups of reeds 10 contained therein may likewise be shifted to and fro into register with corresponding upper rods 12 or 13 controlling the escapements of the center and left hand superposed character groups. For shifting frame 19, lever 25 connected to knob 25^a is loosely pivoted at its inner end to an arm 34 pinned to a cross shaft 35 rotatably supported in two bearing lugs 36 on bracket 30 and in similar bearing lugs 37 and 38 suitably secured to the fixed frame 3. Another arm 39 pinned to shaft 35 is provided with a forked upper end which engages a pin 40 fixed in lugs 41 projecting from the rear of frame 19. Thus, when knob 25^a is pulled forward or pushed rearward, shaft 35 is rotated whereby lever 39 swings the upper end of frame 19 connected to the upper forked end of the lever forward or rearward. For shifting the center frame 18 the lever 26 is loosely pivoted at its inner end to an arm 42 secured to a tubular shaft 43 rotatably supported on shaft 35 between one of the bearings lugs 36 and the lug 37. An arm 44 secured to shaft 43 is provided with a forked upper end which engages a pin 45 fixed in lugs 46 projecting from the rear of frame 18. Thus, when knob 26^a is pulled forwardly or pushed rearwardly, tubular shaft 43 is rotated whereby lever 44 swings the upper end of frame 18 connected to the upper forked end of the lever forward or rearward.

As illustrated in Fig. 3, the character group comprising the small capital alphabet at the left in the upper magazine 8 is simultaneously operative with the numerals and marks and the regular capital letter character groups in the lower magazine 9. Thus, the reed group X in frame 19 has been swung forwardly to register with the twenty-six upper escapement actuating rods 12 belonging to the small capital letter alphabet group in magazine 8 while the reed groups Y and Z are in the rearward position to register the reeds 10 therein with the upper rods 13 belonging to the center and right hand character groups in magazine 9. By thus providing for independent adjustment of each of the reed groups X, Y and Z it will be seen that the keyboard may be connected simultaneously and selectively in part to desired character groups or portions of the complete font in one magazine and in part to other desired character groups or portions of the complete font in another magazine, and such facility for selecting in advance the different portions of each of two complete matrix fonts required for a given piece of composition avoids subsequent distraction and delay in making adjustments of the keyboard connections. Moreover, it will be seen that the construction herein provided may be easily adapted to the division of complete fonts into as many character groups as may be considered desirable merely by further subdivision of the reeds into additional separately adjustable units.

I claim:

1. In a typographical machine, the combination of two superposed magazines each containing a font of matrices and each provided with a series of escapements, a keyboard common to both magazines and having as many finger keys as there are different characters in a complete font, and a series of escapement actuating devices one for each finger key of the keyboard, said

- devices being arranged in independently adjustable groups whereby the keyboard while operative as a whole may be connected simultaneously to both magazines but to different desired non-corresponding portions of the superposed matrix fonts in such magazines.
2. In a typographical machine, the combination of two superposed magazines each containing a font of matrices and each provided with a series of escapements, a keyboard common to both magazines and having as many finger keys as there are different characters in a complete font, and a series of escapement actuating devices one for each finger key, said devices being adjustable independently by groups each into operative relation selectively with the escapements of corresponding superposed portions of the matrices in the respective fonts, whereby operation of the keyboard will effect the release of as many different matrices as comprise a complete font but will release such matrices from any desired combination of non-corresponding portions of the fonts in both magazines.
3. In a typographical machine, the combination of two superposed magazines each provided with escapements and each containing a font of matrices similarly divided into a plurality of character groups with like groups in the respective fonts in superposed relation, a keyboard common to all of the character groups in both fonts, escapement actuating devices operated by the keyboard and divided into as many groups as there are character groups in a single font, and means for adjusting each group of actuating devices independently whereby the keyboard may be operatively connected simultaneously to all of the character groups in one font or to any desired combination of unlike character groups in both fonts.
4. In a typographical machine, the combination of two superposed magazines each provided with escapements and each containing a font of matrices divided into a like number of character groups with similarly disposed groups in the respective magazines comprising superposed pairs, a plurality of groups of escapement actuating devices each group controlling the escapements of a superposed pair of character groups, and separate frames supporting each group of actuating devices for adjustment independently into operative relation with the escapements of one or the other of the pair of character groups controlled thereby.
5. In a typographical machine, the combination of two superposed magazines each provided with escapements and each containing a font of matrices similarly divided into a plurality of character groups with corresponding groups in the respective magazines comprising superposed sets, a keyboard having finger keys equal in number to the characters in a single font and divided into as many groups as there are character groups in a single font, and independently adjustable sets of escapement actuating connections operated by said keyboard, each set of said connections being common to a different group of finger keys and to the escapements of both of a corresponding superposed set of character groups, whereby the keyboard may be connected simultaneously to any desired combination of non-corresponding character groups in both magazines.
6. In a typographical machine, the combination of two superposed magazines each provided with escapements and each containing a different font of matrices divided into a plurality of different character groups with similar character groups in the respective fonts arranged in superposed relation, a keyboard and a series of connections therefrom for actuating the escapements to effect the release of matrices, said keyboard and said connections being divided into corresponding groups equal in number to the character groups in a single font and each group of connections being adjustable independently whereby the keyboard may be connected simultaneously to the escapements of all of the character groups in either one of the fonts or to any combination of dissimilar character groups in both fonts.
7. A combination as in claim 3, wherein each group of escapement actuating devices is mounted in a separate shiftable frame and the adjusting means comprises a manually operated lever for shifting each of said frames.
8. In a typographical machine, the combination of two superposed magazines each provided with escapements and each containing a font of matrices divided into a plurality of character groups with corresponding groups in the respective fonts comprising superposed sets, a single keyboard common to both magazines, a single series of connections therefrom for controlling all of the escapements in response to manipulation of the keyboard, said connections being divided into groups with each group common to a set of superposed character groups, and two fixed series of escapement actuating rods one series for the escapements of each of the magazines, said groups of connections being independently adjustable relative to corresponding rods in the respective series thereof to thereby render the keyboard operative selectively on the escapements of either of the character groups of the respective superposed sets.
9. A combination as in claim 3 wherein the escapement actuating devices are constantly in operative relation with the keyboard and each group of said devices is carried in a separate shiftable frame, and the adjusting means comprises a manually operated lever connected to each frame for swinging the latter relative to the escapements of like superposed character groups.
10. In a typographical machine, the combination of a plurality of superposed main magazines each containing a font of matrices similarly divided into a like plurality of character groups with corresponding groups in the respective magazines in superposed relation, a series of escapements for each magazine, a single keyboard having as many finger keys as there are characters in a font, and a single series of escapement actuating devices divided into as many groups as there are character groups in a font, all of said devices being constantly connected to the keyboard but each group thereof being separately adjustable into operative relation selectively with different desired ones of the superposed character groups in the respective corresponding character group divisions of the fonts in the plurality of magazines.
